UNITED STATES PATENT OFFICE.

LAWRENCE V. DAVIS, OF SOUTH BEND, INDIANA.

ROLLER SKATE.

Application filed June 15, 1925. Serial No. 37,216.

To all whom it may concern:

Be it known that I, LAWRENCE V. DAVIS, a citizen of the United States, residing at South Bend, in the county of St. Joseph and State of Indiana, have invented certain new and useful Improvements in Roller Skates, of which the following is a specification.

The invention relates to roller skates, and has for its object to provide a device of this character, the main frame of which is formed from a single stamping, which may be severed transversely for forming two sections and provided with means for receiving an adjusting bar whereby the frame may be shortened or lengthened according to the size of the foot of the user, and at the same time allowing the same dies to be used for the various sizes of skate frames, thereby reducing the cost of manufacture to a minimum.

A further object is to provide the frame, during the stamping operation with a longitudinally disposed downwardly extending stiffening channel for the reception of an adjusting bar, and the ends of said channel with enlarged depressions, the bottoms of which incline downwardly from the ends of the frame towards the center of the frame, and downwardly struck flanges carried by the bottoms of the depressions for the reception of the roller trucks.

A further object is to provide the opposite sides of the frame, adjacent its forward end with downwardly extending integral flanges having guides therein for the toe clamps, thereby obviating the use of rivets and special separable parts for guiding the toe clamping members.

A further object is to provide the frame adjacent its forward end with a downwardly struck lug substantially centrally thereof, which lug is provided with a segmentally shaped recess engaging an annular groove in the toe clamp adjusting screw for preventing axial movement of the screw during the clamping operation.

A further object is to provide a roller skate frame having a longitudinally disposed stiffening channel, toe clamp guiding flanges and downwardly struck truck receiv-

ing flanges, all of which parts are formed from a single piece of metal and in a single stamping operation.

With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawing:—

Figure 1 is a top plan view of the frame, before it is severed transversely. 65

Figure 2 is a side elevation of the frame.

Figure 3 is a top plan view of the frame showing the same severed transversely.

Figure 4 is a top plan view of the roller skate. 70

Figure 5 is a vertical longitudinal sectional view through the roller skate.

Figure 6 is a transverse sectional view taken on line 6—6 of Figure 5.

Figure 7 is a transverse sectional view taken on line 7—7 of Figure 4. 75

Referring to the drawings the numeral 1 designates the main body of the frame of the skate, which body is provided with a downwardly struck longitudinally disposed channel 2, which stiffens the body 1 and forms a longitudinally disposed recess 3, which receives the ends of the adjusting bar 4 after the skate has been formed, and the frame severed transversely at 5 for forming front and rear skate sections 6 and 7. The ends of the channel 2 terminate in downwardly struck enlarged recesses 8, the bottoms 9 of which incline downwardly from the outer end of the sections 6 and 7 towards the center of the skate, and into which recesses the ends of the adjusting bar 4 extend. Bottoms 9 of the recesses 8 are provided with downwardly extending parallel flanges 10, which are struck out from the bottoms 9, and which flanges are provided with apertures 11 for the reception of the pins 12, which pins extend through the flanges 13 of the skate trucks 14 and rockably secure said trucks to the skate frame. It will be seen 80

90

95

100

that the frame and the channels as well as the enlarged recesses 8 and flanges 10 may be formed in a single stamping operation and from a single piece of metal. The rear 5 end of the skate section 7 is provided with a heel guard 15, which heel guard is provided with strap receiving slots 16, and the heel guard is formed during the single stamping operation referred to. Trucks 14 10 are formed from a single piece of metal bent to form, and to provide cylindrical portions 17 which form bearings for the axles 18 of the skate, and on the ends of which axles rollers 19 are rotatably mounted, which rollers may be of any construction, however they are preferably provided with anti-frictional bearings 20 as shown in Figure 6.

Extending downwardly from the opposite sides of the skate sections 6 adjacent its forward end are longitudinally disposed flanges 21, which flanges are struck downwardly during the formation of the skate frame, and are provided with guide bearing recesses 22 in which the skate clamping members 23 20 are slidably mounted, therefore it will be seen it will not be necessary to use rivets and other separable parts for forming guides for the clamping members 22, and the guide recesses may be formed during the 25 stamping operation if desired. Clamping members 23 extend under the frame sections 6 and are provided with downwardly extending flanges 24, through which are threaded the right and left handed portions 25 of the adjusting screw 26, therefore it will be seen that when the adjusting screw 26 is rotated the toe clamping member, 23 will be moved towards or away from each other according to the direction of rotation 40 of the adjusting screw. To insure movement of the clamping members 23 relative to each other and to the skate frame, the skate section 6 is provided with a downwardly struck lug 27, the lower end of which is provided 45 with a segmentally shaped recess 28, and which recess receives the reduced portion 29 of the adjusting screw 26, consequently axial movement of the adjusting screw is prevented during its rotation in either direction. Interposed between the trucks 14 50 and the bottoms of the recesses or depressions 8 are yieldable cushions 30, which cushions allow transverse rocking of the skate frame in relation to the truck during 55 a skating operation, but normally maintain the axles 18 in a parallel plane to the frame.

From the above it will be seen that a roller skate is provided wherein the frame, the reinforcing channels, truck connecting means, 60 toe clamping member guides and adjusting screw flange are all formed from a single stamping thereby obviating the use of rivets and a multiplicity of parts, consequently the skate can be cheaply manufactured and sold. 65 It will also be seen that the frame can be

easily severed and used for different sizes of skates, and may be extended to various lengths by means of the adjusting bar 4, through which bolts 31 extend and which bolts extend through the opposite sides of 70 the channel members 2. By this adjusting means it is obvious a single set of dies may be used for manufacturing the skate frame, thereby obviating the use of a plurality of sets of dies for various sizes of skates. 75

The invention having been set forth what is claimed as new and useful is:—

1. A skate comprising forward and rear frame sections, downwardly struck alined reinforcing channels carried by said frame sections, truck attaching means in the bottom of said channels, and an adjusting bar disposed in said channels and connecting said frame sections. 80

2. A skate comprising forward and rear frame sections, downwardly struck alined reinforcing channels carried by said frame sections, downwardly struck truck attaching means in the bottoms of said channels, trucks attached to said truck attaching means, a connecting bar in said channels and connecting said sections, and adjusting means cooperating with the frame sections and the bar whereby they may be adjusted towards and away from each other. 95

3. A skate comprising forward and rear frame sections, downwardly struck alined reinforcing channels carried by said frame sections, the outer ends of said channels terminating in enlarged downwardly struck portions, the enlarged downwardly struck portions having their bottoms inclined downwardly and inwardly from the ends of the skate, said bottoms being provided with downwardly struck spaced flanges, skate trucks attached to said flanges, and an adjusting bar disposed in the channels and forming means for adjustably connecting the frame sections together. 100

4. The combination with a skate comprising adjacent front and rear sections, alined channels in said sections, an adjusting bar in said alined channels and connecting said sections together, of downwardly struck spaced flanges in the outer ends of the channels, and trucks connected to said downwardly struck flanges. 110

5. The combination with a skate comprising front and rear sections having alined downwardly struck channels, a connecting bar disposed in said channels, the ends of said channels being provided with downwardly and inwardly inclined bottoms, of downwardly and outwardly inclined struck out flanges carried by said bottoms, and skate trucks attached to said flanges. 120

6. A skate frame comprising a body portion, a downwardly struck longitudinally disposed reinforcing channel carried by the body portion, the ends of said channel ter- 130

minating in upwardly inclined portions, downwardly struck spaced truck receiving flanges carried by the inclined portions, and means for attaching a truck to said flanges.

5 7. A skate frame comprising a body portion, a downwardly struck longitudinally disposed reinforcing channel carried by the

body portion, the ends of said channel terminating in upwardly inclined portions, downwardly directed spaced flanges carried 10 by said inclined portions, and means for attaching a truck to said flanges.

In testimony whereof I affix my signature.

LAWRENCE V. DAVIS.
